APPARATUS FOR CLEANING RUGS

William T. Stride, Rochester, N. Y., assignor to
The American Laundry Machinery Company,
Norwood, Ohio, a corporation of Ohio

Application July 9, 1930, Serial No. 466,772

16 Claims. (Cl. 15—6)

This invention relates to apparatus for cleaning rugs and more particularly to apparatus of this character employing operating devices for removing the dust and dirt from rugs, carpets and other fabrics, one object of the invention being to provide a simple and effective apparatus for thoroughly removing a maximum amount of the dust and dirt adhering to a rug, carpet or other fabric without loosening, tearing or otherwise injuring the fibers thereof.

Another object is the provision of a relatively simple, efficient and durable mechanism, easy to control and operate, for carrying out such cleaning operation. A further object is to provide a machine for the purpose described capable of performing beating, brushing and vacuum cleaning operations upon rugs and other fabrics of any thickness in an effective, rapid and efficient manner without injury to the rugs and without allowing the escape of dirt and dust into the surrounding atmosphere.

A further object is the provision of an efficient apparatus of the character described wherein the rug or a portion thereof is caused to flex or bend in a novel manner so as to effectively loosen and remove the dirt which has become matted in the interstices of the fabric. Still a further object is the effective utilization of vacuum or suction in connection with the novel bending or flexing process to expedite the thorough removal of dust and dirt matted in the fabric.

To these and other ends the invention resides in certain improvements and combinations of parts, all as will be hereinafter more fully described, the novel features being pointed out in the claims at the end of the specification.

In the drawings:

Fig. 1 is a side elevation of the device, certain of the operating parts being shown in section and others in dotted lines;

Fig. 2 is a sectional view taken on the line 2—2 of Fig. 3;

Fig. 3 is a plan view of the device having certain parts partially broken away;

Fig. 4 is a front elevation with the brush casting omitted and certain parts broken away so as to clearly disclose the beater elements;

Fig. 5 is a sectional view taken on the line 5—5 of Fig. 3, showing a beating tool in its upper position;

Fig. 6 is a sectional view similar to Fig. 5, showing a beating tool in its lower position, and

Fig. 7 is a fragmentary rear elevation looking from the left end of Figs. 1, 5 and 6.

Similar reference numerals throughout the several views indicate the same parts.

The present embodiment of the invention provides apparatus of the nature described which is particularly advantageous in plants where cleaning operations are carried out on a large scale and where it is desired to quickly and effectively clean rugs and other fabrics in a thorough and uniform manner. To this end the invention, as disclosed, is embodied in a machine having 10 beating means for delivering impacts on the rug to be cleaned, a vacuum cleaning means for rapidly carrying away the dust removed by the tool, and a brushing or sweeping means for removing traces of dust not carried away by the vacuum means. 15

Referring more particularly to the drawings, showing a preferred embodiment of the invention, 1 designates the base of the apparatus having thereon a conveying means for engaging a rug, herein shown in the form of a pair of feed rollers, 2, 3; a beating means generally indicated at 4; a vacuum cleaning means 5; and a brushing means herein shown in the form of a pair of rotary brushes, 6, 7.

The base 1 is provided with suitable upstanding portions 8, 8 at each side of the machine which form the framework for supporting the parts to be described later. A horizontal plate portion 9 on the base extends between the upstanding portions 8, 8 and supports on its upper surface a pair of angle castings 10 and 11 which are suitably secured centrally on the plate portion 9 with their adjacent vertical portions 12 and 13 somewhat spaced apart to form the throat portion of the vacuum cleaning means which will be described hereinafter.

For the sake of convenience of reference, the right hand side of the machine as seen in Fig. 1 will be referred to as the front and the left side as the rear of the machine.

The feed rollers, beating means and brushes are disposed transversely of the machine between the upstanding frame portions 8, 8. It is desirable that the corresponding feed rollers and brushes be arranged for movement toward and from each other for the purpose of facilitating starting of the rug between the rollers and determining the pressure of the brushes upon the rug. In the present embodiment the lower roller and brush are stationary on the frame 1, and the upper roller and brush are vertically movable.

The lower roller 3 is mounted on a shaft 14 journalled in bearing brackets 15 which are bolted or otherwise secured to the angle casting 10.

The upper roller 2, the upper brush 6 and the 55

beating means 4 are operatively supported between vertically movable slide members 16 guided between pairs of inwardly extending lugs 17 on the upstanding portions 8, 8, see Fig. 3. The roller 2 is supported on a shaft 18 journalled in the slides 16. One end of the shaft extends outwardly of one of the frame portions 8 through a slot 19 formed therein and is provided with suitable gear means, hereinafter described, for driving the roller.

10 The rollers 2 and 3 may be of any suitable construction and are provided with any suitable friction covering such as rubber or cloth to enable them to engage and feed the rug into the machine.

15 The beating means 4 in the present embodiment is mounted on a beam member 20 which extends between the slides 16 and is secured at its ends to inwardly projecting lugs or brackets 21 formed on the slides 16. A plurality of bracket members 22 are secured along the beam member 20, each bracket comprising two arm portions 23 with a connecting portion 24 therebetween thus forming a bracket roughly U-shaped as viewed in plan. The connecting portions 24 of each bracket are bolted at 25 to the web of the beam 20. Each bracket 22 carries a beating tool which comprises a pair of reciprocating rods 26 vertically slidable in apertures in enlarged bosses 27 on the ends of arms 23 and secured at spaced 30 points to a head member 28 in which an impact rod 29 is imbedded. The rods 26 of each pair are connected at their upper ends to a cross rod 30. A suitable adjusting means in the present instance indicated by an adjusting nut 31, is provided for decreasing or increasing the distance 35 between the cross rod 30 and the impact rod 29.

The beating tool may be operated in various ways to deliver impacts to a rug therebeneath, but in the present embodiment the operating means 40 is shown as a cam shaft 32 extending along the beam 20 and journalled in each pair of arms 23 on brackets 22 and which supports cams 33 thereon arranged for alternate lifting or releasing of the beating tools. A roller 34 is provided on each 45 cross rod 30 and is positioned so as to be engaged by the cam in its rotation with shaft 32. A coil spring 35 surrounds the lower end of the rods 26 and bear against the lower side of bosses 27 and the upper side of the head 28 to cause 50 the head 28 to move downward when the cam passes from engagement with roller 34. Referring to Figs. 5 and 6, it will be seen that when the cam 33 is rotated in the direction shown by the arrow, it will engage roller 34 and thereby lift 55 the beating tool against the tension of the springs 35 and, upon further rotation of the cam, it will pass from engagement with the roller and allow the springs to force the tool downwardly, thus causing it to deliver a sharp impact against the rug therebeneath to effectively separate the dust therefrom.

60 The cams 33 may all be secured in the same position on shaft 32, if desired, but it has been found preferable to arrange the cams on the shaft in varying angular positions (see Figs. 1 and 4) so that the adjacent beating tools will not operate simultaneously. The cams may also be arranged so that no two beating tools will operate at the same time. The particular sequence of operation, however, is not material to the present invention.

65 Means are provided for yieldably supporting the rug at the point where the beating tool strikes. It is desirable to so correlate the yielding supporting means with the beating tool that when the 70 tool strikes the rug there will be an impact which

will tend to remove the dust and after the impact the tool will continue to move downwardly so as to flex or bend the rug at this point thereby opening the weave to loosen matted dirt from the interstices thereof. It is also desirable that the yielding supporting means be arranged so as to hold the rug, or a portion thereof in an upwardly flexed position when the beating tool is not in engagement with the rug. In connection with the supporting means above described it has been 10 found preferable to provide a vacuum means to act on the rug at the time of the flexing operation. The above mentioned functions may be carried out by various forms of mechanism and the flexing operation may or may not be accompanied with a beating operation in order to produce desirable results upon the rug or other fabric.

15 In the present embodiment of the invention the yielding supporting means for the rug is positioned within the throat portion of the vacuum cleaning means 5 and these structures will, therefore, be described together. As stated above, the angle castings 10 and 11 are positioned on the plate portion 9 with the upstanding portions 12 and 13 adjacent and spaced apart. The upstanding portions thus form part of a throat for the vacuum means. Between the angle castings 10 and 11 the horizontal plate portion 9 is formed with an opening into which a neck 36 of a vacuum 20 chest 37 is fitted as shown in Fig. 5. On the upstanding part 12 is secured a bracket member 38 which serves also as a continuation of one side of the vacuum throat formed by parts 12 and 13. The bracket member 38, in the present instance, 25 extends toward the rollers 2 and 3 and has an integrally formed plate portion 39 extending forwardly toward the beating mechanism. The plate 39 serves to support the rug immediately after passing from the rollers 2 and 3 and before 30 it is engaged by the beating means. While this plate can be horizontal or inclined in either direction, in the preferred form of the invention it is inclined upwardly toward the beating means 35 as shown in Fig. 5. A somewhat similar plate 40 portion to the plate 39 is formed on the upstanding part 13 of the angle casting 11 serving both as a part of the vacuum throat structure and as a supporting means for the rug. This is shown in the form of an angle bracket having a depending 45 part 40, bolted or otherwise attached to part 13, and a surface 41 which projects toward the brushes 6 and 7 and serves to support the rug 50 after it leaves the beating means until it passes between the brushes.

55 The yielding supporting means is shown in the present instance in the form of a plurality of lengths of coiled spring wire 42 which are supported at the entrance of the vacuum throat formed between the adjacent edges of plates 39 and 41. The length of the coils of wire is preferably the same as the length of the beating tools, 60 see Fig. 4.

65 Means are provided for yieldingly supporting the coils or springs 42 for vertical movement within the vacuum throat. The means preferably comprises a plate 43 pivoted at 44 on the bracket 38 held in position by a spring 45 so that the free edge of the plate contacts the lower part of the coil spring 42 and holds the upper surface of the coil spring 42 normally somewhat above the adjacent edges of plates 39 and 41. It will be understood 70 that the pivoted plates 43 substantially correspond in length to the coil springs and the beating tools.

The coil springs are preferably formed with their convolutions spaced apart sufficiently to allow dirt and dust to pass downwardly there-between into the vacuum throat. The individual convolutions thus provide spaced supporting elements for supporting the rug beneath the beating tool.

It is apparent from the foregoing description that the rug, in the present embodiment of the invention, will be normally supported in an upwardly flexed condition beneath the beating tool and when the beating tool strikes the rug at this point it first produces an impact, tending to remove the loose dust in the rug, and then travels downwardly depressing the coil 42 into the vacuum throat against the action of spring 45 until the rug portion across the vacuum throat has been brought to a downwardly flexed condition substantially as indicated in Fig. 6. The cam then raises the beating tool and spring 45 brings the parts back into normal positions. It should be understood that the time interval during which the beating and flexing operations take place is relatively short so that no material amount of resistance will be offered to the passage of the rug through the machine. The movement of the rug is further facilitated and made substantially uniform by the fact that the beating tools operate at different times.

The brushes 6 and 7 as previously stated are supported for relative separating movement, the upper brush 6, in the present instance, being movable and the lower brush 7 being stationary. The upper brush may be mounted for movement in fixed relation with the roller 2 or independently thereof. In the present embodiment the brush 6 is shown fixed on a shaft 46 which is journalled in bearings 47 on the slides 16 (see Fig. 2) so as to move vertically when the slides 16 are raised. The lower brush 7 is fixed on a shaft 48 journalled in bearings 49 on the base frame 1. Any suitable type of rotary brush may be utilized, the particular construction being immaterial to the present invention. The brushes 6 and 7 are preferably driven in opposite directions so that their peripheries move in a direction to feed the rug between them out of the machine. The brushes will, however, be driven with a peripheral speed greater than the speed of movement of the rug to thereby produce the desired brushing effect.

Means are provided for raising the slides 16, 16 to raise the upper roller and brush and the beating means. For this purpose there is shown, as seen in Fig. 1, a rod 50 secured to the slides and extending therebetween the ends of which extend outwardly through slotted or cut out portions 51 in the upper end of the frame members 8, 8. On the ends of rod 50 are secured cam levers 52 each having a cam surface 53 and an adjoining flat surface 54. A rigid lug or shelf member 55 is formed on the outer side of the frame portions 8, 8 for cooperation with the cam levers. On reference to Fig. 1, it will be seen that when the upper end 65 of cam lever 52 is moved downwardly and to the left, cam surface 53 will bear against the lug 55 causing rod 50 to move upwardly along the slots 51 until the flat surface 54 comes to rest on the lug. The slides 16 are thus held in their uppermost position. When a rug is to be fed through the machine the slides are lowered by a reverse operation of the levers 52 so that the weight of the parts carried by the slides is imposed upon the rug thus forming a yielding means for holding the rollers and brushes in contact with the rug so that rugs

of any thickness may be cleaned by the machine. It will be seen further, as the upper roller and brush bear a fixed relation to each other, the spacing between the brushes is substantially the same as between the rollers so that there will be no danger of the brushes injuring the fibers of the rug since they will always be held apart a distance determined by the spacing of the rollers in engagement with the rug.

Means are provided for driving the parts from any suitable source of power. In the present instance, the means for driving the rollers 2 and 3 comprises a pair of worm wheels 56 and 57 fixed respectively to projecting ends of shafts 18 and 14 and meshing respectively with worms 58 and 59 splined on a vertical shaft 60. The shaft 60 has a bevel gear 61 at its upper end which meshes with a similar bevel gear 62 on shaft 63 journalled in bearings 64 at the top of frame member 8 and provided with a belt pulley 65 driven from any suitable power source.

The means for driving the cam shaft for the beating tool is shown as a pulley 66 on the end of the cam shaft 32 which is driven by a belt 67 connected preferably to an overhead shaft not shown. In practice this belt is suitably provided with any conventional automatic belt tighter to allow it to function properly in any vertically adjusted position of the cam shaft with the slides 16.

The upper brush 6 may be driven in a similar manner as the cam shaft is driven. In the present instance, there is shown a pulley 68 on the end of shaft 46 over which a belt 69 runs to a suitable power connection such as an overhead shaft. This belt in practice is also provided with automatic belt tightening means for the reasons stated above.

The lower brush 7 is driven by a pulley 70 on its shaft 48, the pulley being connected to a source of power through belt 71.

Means are provided for enclosing the brushes 6 and 7 to prevent the escape of dust into the surrounding atmosphere. For this purpose, a lower casing portion 72 is secured to the front 45 of the machine and is provided with a horizontal table portion 73 which serves to support the rug after passing from between the brushes. An upper casing portion 74 surrounds the upper brush and is constructed of sufficient height to allow 50 for vertical movement of the brush when the slides 16 are raised. The casing 74 terminates a short distance above the table portion 73 to allow for outward passage of rugs of any thickness. The opening between the casing portions is 55 closed by a flexible flap 75 secured to the upper casing 74 and arranged so as to be swung or bent upward by the outward passage of a rug through the machine. The casings are thus practically air tight.

It is desirable to provide means for removing from the casing the dust formed by the action of the brushes. To this end each casing is in communication with the vacuum chest. The upper casing portion 74 is provided with one or more openings 76 in its ends for the reception of a suction conduit which connects with the vacuum chest 37. The lower casing in the present instance is in communication with the vacuum throat by means of an opening 77 formed in the upright portion 13 of angle casting 11.

The vacuum chest may be connected with any suitable source of vacuum such as a suction pump, as will be obvious to any person skilled in the art.

In the operation of the device the slides 16 are first raised by the cam lever 52 in the manner previously described, and the operating parts are set in motion through their respective driving connections. The end of a rug or other fabric to be cleaned is then inserted between the rollers 2 and 3 and the slides 16 are then moved downwardly by means of the cam lever. The rollers 2 and 3 upon coming into engagement with the rug force the rug along plate 39 and over coil springs 42 so as to bring it beneath the beating tools. The cams 33 are rotating at considerable speed thus alternately moving the beating tools up against the compression of their springs 35 and allowing them to move quickly downward when the cam passes out of contact with the roller 34. Each beating tool produces a rapid succession of sharp impacts upon the rug immediately above its companion coil spring 42.

As already explained, the beaters preferably do not operate in unison, but are operated in any predetermined sequence. The result being that the rug receives a quick succession of independent impacts transversely of its length as it is moved along by rolls 2 and 3 and brushes 6 and 7.

When the beating tool strikes the rug opposite coil spring 42 it produces first a relatively sharp impact and afterward, as it overcomes the inertia of the coil, it causes downward movement of the same within the vacuum throat to thus bring the rug to a downwardly flexed condition. After the beater head moves upwardly, the spring 45 forces the plate 43 up to its position as shown in Fig. 5 and the plate in turn forces the coil spring 42 up to the position shown in the same figure. It is apparent that the action of the beater is to first give the rug a sharp blow after which the rug is moved from an upwardly flexed to a downwardly flexed position. This movement tends to separate the fibres very thoroughly and loosen the dust therein so as to facilitate its removal by the vacuum means.

The dust and dirt loosened by the beaters passes between and around the coils of the springs 42 down through the vacuum throat and into the vacuum chest where it may be collected in a suitable manner.

After the rug leaves the beater mechanism it passes along the surface 41 and between the brushes 6 and 7 where any remaining dirt and dust on the surfaces of the rug is removed and conducted through the openings 76 and 77 to the vacuum chest. When the rug has passed through the machine the slide 22 is raised preparatory for the reception of another rug.

The present invention thus provides an effective apparatus for cleaning rugs and like fabrics to produce uniform cleaning effects thereon in a rapid, thorough and uniform manner without injurious effect on the fibers of the fabric. The invention likewise provides a comparatively simple, practical and reliable apparatus by means of which the cleaning may be conveniently carried out.

I claim as my invention:

1. In a rug cleaning machine, in combination, means for feeding a rug through said machine comprising upper and lower feed rollers, an upwardly movable supporting element on said machine in which said upper feed roller is journaled, a vertically reciprocating beating tool mounted on said vertically movable element, a rotatable brush mounted on said vertically movable element positioned adjacent said beating tool, a rotatable brush on a fixed portion of the machine

below said first mentioned brush, and means for raising and lowering said supporting means, so that said feed rollers and brushes may be moved into operative or inoperative positions with respect to each other.

2. In a rug cleaning machine, a frame, rug feeding means including a supplemental frame supported by and movable relative to the first named frame in response to rug thicknesses, a floor over which said rug travels, a gap in said floor forming a suction throat, resilient means disposed in said throat for maintaining the part of said rug in registry with said throat in upwardly flexed position, a beating means carried by said movable supplemental frame whereby to deliver impacts of equal force to rugs of varying thickness and in registry with said throat for delivering impacts to the rug, suction means for drawing dust or the like through said throat and away from the rug, and a brush means effective on said rug subsequently to said beating means.

3. In a rug cleaning machine, a frame, rug feeding means including a supplemental frame supported by and movable relative to the first named frame in response to rug thicknesses, a floor over which said rug travels, a gap in said floor forming a suction throat, resilient means disposed in said throat for maintaining the part of said rug in registry with said throat in upwardly flexed position, a beating means carried by said movable supplemental frame whereby to deliver impacts of equal force to rugs of varying thickness and in registry with said throat for delivering impacts to the rug, suction means for drawing dust or the like through said throat and away from the rug, and a brush means effective on said rug subsequently to said beating means, there being means establishing communication between said suction means and the rug at the point where said brushes are effective thereon.

4. A rug cleaning machine, comprising a main frame, a supplemental frame carried thereby and movable thereon, a reciprocating rug beating means carried by said supplemental frame for delivering impacts to the rug, and means for supporting said supplemental frame on the rug whereby it will move relative to the main frame in response to rug thicknesses and thereby cause said beating means to deliver impacts of equal force to rugs of varying thickness.

5. A rug cleaning machine, comprising a main frame, a supplemental frame carried thereby and movable thereon, a reciprocating rug beating means carried by said supplemental frame for delivering impacts to the rug, means for supporting said supplemental frame on the rug whereby it will move relative to the main frame in response to rug thicknesses and thereby cause said beating means to deliver impacts of equal force to rugs of varying thickness, and means for flexing the portion of the rug in registry with said beating means and prior to contact of said beating means with said portion of the rug.

6. A rug cleaning machine, comprising a main frame, a supplemental frame carried thereby and movable thereon, a reciprocating rug beating means carried by said supplemental frame for delivering impacts to the rug, means for supporting said supplemental frame on the rug whereby it will move relative to the main frame in response to rug thicknesses and thereby cause said beating means to deliver impacts of equal force to rugs of varying thickness, and guide means co-

operating with said beating means for flexing the rug in advance of the point struck by said beating means.

7. A rug cleaning machine, comprising a main frame, a supplemental frame carried thereby and movable thereon, a reciprocating rug beating means carried by said supplemental frame for delivering impacts to the rug, and means including a rug feeding means for supporting said supplemental frame on the rug whereby it will move relative to the main frame in response to rug thicknesses and thereby cause said beating means to deliver impacts of equal force to rugs of varying thickness.

15 8. A rug cleaning machine, comprising a main frame, a supplemental frame carried thereby and movable thereon, a reciprocating rug beating means carried by said supplemental frame for delivering impacts to the rug, means including a rug feeding means for supporting said supplemental frame on the rug whereby it will move relative to the main frame in response to rug thicknesses and thereby cause said beating means to deliver impacts of equal force to rugs of varying thickness, and means for flexing a portion of the rug in registry with said beating means and prior to contact of said beating means with said portion of the rug.

25 9. A rug cleaning machine, comprising a main frame, a supplemental frame carried thereby and movable thereon, reciprocating beating means carried by said supplemental frame for delivering impacts to the rug, upper and lower rotatable brushes effective on opposite sides of the rug, one of said brushes being carried by said supplemental frame, and means for supporting said supplemental frame on said rug whereby the supplemental frame, beating means and the one brush will be movable towards and away from the rug in response to rug thicknesses to thereby cause said beating means to deliver impacts of equal force to rugs of varying thicknesses and to vary the spacing between said brushes.

35 10. A rug cleaning machine, comprising a main frame, a supplemental frame carried thereby and movable thereon, reciprocating beating means carried by said supplemental frame for delivering impacts to the rug, upper and lower rotatable brushes effective on opposite sides of the rug, one of said brushes being carried by said supplemental frame, and means including a rug feeding means for supporting said supplemental frame on said rug whereby the supplemental frame, beating means and the one brush will be movable towards and away from the rug in response to rug thicknesses to thereby cause said beating means to deliver impacts of equal force to rugs of varying thickness and to vary the spacing between said brushes.

45 11. A rug cleaning machine, comprising a main frame, a supplemental frame carried thereby and movable thereon, reciprocating beating means carried by said supplemental frame for delivering impacts to the rug, upper and lower rotatable brushes effective on opposite sides of the rug, one of said brushes being carried by said supplemental frame, means for supporting said supplemental frame on said rug whereby the supplemental frame, beating means and the one brush will be movable towards and away from the rug in response to rug thicknesses to thereby cause said beating means to deliver impacts of equal force to rugs of varying thickness and to vary the spac-

ing between said brushes, and means for flexing a portion of the rug in registry with said beating means and prior to contact of the beating means with said portion of the rug.

5 12. A rug cleaning machine, comprising a main frame, a supplemental frame carried thereby and movable thereon, reciprocating beating means carried by said supplemental frame for delivering impacts to the rug, upper and lower rotatable brushes effective on opposite sides of the rug, one of said brushes being carried by said supplemental frame, means including a rug feeding means for supporting said supplemental frame on said rug whereby the supplemental frame, beating means and the one brush will be movable towards and away from the rug in response to rug thicknesses to thereby cause said beating means to deliver impacts of equal force to rugs of varying thickness and to vary the spacing between said brushes, and guide means cooperating with said beating means for flexing the rug in advance of the point struck by said beating means.

10 13. A rug cleaning machine, comprising a main frame, a supplemental frame carried thereby and movable thereon, a floor over which said rug travels, a gap in said floor, resilient means disposed in said gap for maintaining the part of the rug in registry with the gap in upwardly flexed position, means including a rug feeding means for supporting said supplemental frame on the rug whereby the supplemental frame will be movable towards and away from the rug in response to rug thicknesses, and a beating means carried by said supplemental frame and in registry with the gap for delivering impacts to the rug.

15 14. A rug cleaning machine, comprising a main frame, a supplemental frame carried thereby and movable thereon, a floor over which said rug travels, a gap in said floor, resilient means disposed in said gap for maintaining the part of the rug in registry with the gap in upwardly flexed position, means including a rug feeding means for supporting said supplemental frame on the rug whereby the supplemental frame will be movable towards and away from the rug in response to rug thicknesses, a beating means carried by said supplemental frame and in registry with the gap for delivering impacts to the rug, and said floor adjacent said gap cooperating with said beating means for flexing the rug in advance of the point struck by said beating means.

20 15. In a machine of the class described, the combination of beating means, and means for yieldingly supporting a fabric therebeneath comprising an elongated member, a member extending along and partly beneath the first-named member, said second-named member being pivotally supported for movement toward and from the first-named member, and means for yieldingly biasing said second-named member toward said first-named member.

25 16. In a rug cleaning machine, beating means, spaced supports for carrying a rug therebeneath, said beating means being mounted for movement between said supports, and to points above and below the plane of the same, yielding means for holding the portion of said rug between said supports at a point above the plane of said supports, and said beating means functioning to move the portion of the rug struck thereby to a point below the plane of said supports.
